UNITED STATES PATENT OFFICE.

OLIVER D. HUNT, OF COLUMBUS, OHIO.

SWITCH-OPERATING MECHANISM.

SPECIFICATION forming part of Letters Patent No. 740,279, dated September 29, 1903.

Application filed January 19, 1903. Serial No. 139,505. (No model.)

To all whom it may concern:

Be it known that I, OLIVER D. HUNT, a citizen of the United States of America, residing at Columbus, in the county of Franklin and 5 State of Ohio, have invented certain new and useful Improvements in Switch-Operating Mechanism, of which the following is a specification, reference being had therein to the accompanying drawings.

10 This invention relates to improvements in mechanism for operating switch-points from a moving car; and its object is to provide a mechanically-operated device so constructed that the switch-point may be operated in the 15 same manner as the ordinary and well-known switch and the actuating member of which, whether the switch-point has been previously thrown by the means carried by the car, by the car-wheel engaging the same, or by a 20 pinch-bar, will always be in a position to be engaged by the means carried by the car and will always be in position to throw the switch-point.

It is also an object of this invention to provide 25 a yielding connection between the switch-point and the member which imparts motion thereto, so that if the point is prevented from moving by any obstruction getting in between it and the rail no injury will result; and it is 30 also an object of the invention to provide a device in which every movement is positive, no springs being relied upon to actuate the parts, and to provide a very cheap and simple construction not liable to get out of order 35 or broken, all as hereinafter more fully described, reference being had to the accompanying drawings, in which—

Figure 1 is a plan view showing the road-bed, rails, switch-point, and mechanism for 40 operating the point in operative position; Fig. 2, a longitudinal section through the casing for the actuating-wheel and its transmission-gearing; Fig. 3, a vertical section through the casing for the crank-disk and connecting- 45 rod and showing the compression-spring cylinder of the connecting-rod and the switch-point in section. Fig. 4 is a transverse section on the line $x-x$ of Fig. 2. Fig. 5 is a side elevation of the operating-foot and its supporting and actuating mechanism carried by 50

the car. Fig. 6 is a diagram illustrating the operation of the device.

A A are the rails of the main track, B B the rails of the switch or branch, and C the switch-point, all constructed and arranged in 55 the usual manner.

Located at any desirable point, preferably between the rails in the road-bed and at a suitable distance from the switch-point, is a 60 casing or box D, having a removable top D', provided with a groove D², in the bottom of which groove is an opening through which the teeth or lugs E of the actuating or star wheel E project; said wheel being fast upon a shaft F, journaled in bearings in the sides 65 of the casing. Secured on the shaft F to turn with the wheel E is a bevel-gear G, and in mesh with said gear is a bevel-gear H of smaller diameter secured upon the end of a shaft I, which extends outward through a 70 suitable bearing on the casing to a point opposite the switch-point, where it extends into a second casing J and is provided with a crank-disk K, which is secured to its end. A connecting-rod L is pivotally secured to 75 said disk at one end by a wrist-pin L' and at its opposite end to the lower end of a stud M, secured to the bottom of the switch-point C and extending downward into the casing J through a slot M' in the frog of the track. 80 The connecting-rod L is divided or made in two parts connected by a cylinder L², said cylinder being secured to the end of one part of the rod, and the adjacent end of the other part extends into the cylinder and is provided with a head L³, engaged at one side by one end of a coiled spring N, sleeved on the 85 rod and engaging the end of said cylinder at its other end, and at its opposite side the head is engaged by a coiled spring N', interposed between said head and the other end of the cylinder, so that the rod may be extended or contracted a short distance against the action of said springs.

A device for operating the actuating-wheel 95 E is carried by each car, so that the switch-point may be operated from the moving car, said wheel being placed at such a distance from the switch-point that the same will be thrown before the car-wheel reaches the point 100

and will remain in that position until moved by the operating device on another car, by the wheels of a car coming in the opposite direction, or by the use of a pinch-bar. This device consists of a rectangular bar O, movable vertically in a suitable bearing on a bracket P, secured to the truck-frame Q or to any other convenient part of the car, and attached to the lower end of said bar by means of a hinge R' is a foot R, said hinge being located at the rear angle of the bar and foot portion, and the foot is normally held in line with the bar by a coiled spring R², attached at its ends to the forward extensions R³ and R⁴ on the bar and foot, respectively. The upper end of said bar O is provided with a head O', and sleeved on the bar between the head and the bracket P is a coiled spring O², which acts to normally hold the bar in its elevated position with the foot raised to pass over the actuating-wheel E without contacting the same. To lower the foot R, a toggle-lever S is provided consisting of two links pivoted together at their adjacent ends and to the bracket P and bar O at their opposite ends, a yoke S² being secured to the bars at the point where they are secured together, and a rod S' is secured to said yoke to straighten out the toggle-lever. The rod S' is passed through an ear S³ on the bracket, and a spring S⁴ is sleeved on said rod between the ear and the yoke to throw the toggle-lever off its center. Any suitable means may be provided within the vestibule of the car for actuating the rod S' and by means of which the motor-man as his car approaches the actuating-wheel E may lower the foot R, so that it will enter the groove D² and as the car moves toward the switch-point will engage the projecting lug E' of the wheel E and turn the same. I prefer to make the groove comparatively narrow, so as to lessen the liability of injury to the wheel E from vehicle-wheels, and the top D' is made as thick at the center as is necessary to protect the lugs E' and is tapered off toward its edges, so that there will be no sharp angles projecting upward from the road-bed to interfere with traffic. The foot is also hinged to the bar O, so that if the groove is obstructed, the wheel E is prevented from turning by reason of the switch-point being obstructed or from other causes, or if said foot should strike any immovable obstruction it will spring back to the position shown in dotted lines and pass over the obstruction without injury to the device.

Referring to Fig. 6, it will be seen that when the foot R engages the lug on wheel E said wheel will be turned in the direction indicated by the arrow, carrying the engaged lug from the position marked a to position b, and through the medium of the gears G and H and the shaft I said wheel will turn the crank-disk K in the direction also in-

dicated by an arrow, said gears being so proportioned that the wrist-pin which secures the connecting-rod L to the disk will be moved from the position marked c to the position marked d, which is more than one-half of a revolution of the disk. 70

The diameter of the circle described by the path of travel of the wrist-pin is considerably greater than the distance between the rails A B or the throw of the switch-point, so that 75 when the switch-point is against the rail B the wrist-pin will be at c and not on the dead-center of the crank. The switch-point may therefore be moved over toward the rail A by the wheel of a car coming toward it on 80 track B or by a pinch-bar, and the crank-disk when the point is so operated will always be turned backward or in a direction opposite to that in which it is turned by the actuating-wheel, and this backward movement of the disk will be only equal to the movement of the point, so that if the point was thrown by a car-wheel or otherwise from rail B over to rail A the wrist-pin would be moved backward to position e, which backward movement of the crank-disk would turn the actuating-wheel backward, bringing the lug E' to position f, when it may be engaged by the operating-foot on a car coming along track A and be again turned to position b, 90 moving the switch-point over to rail B again. The parts are also in such a position when the lug E' is in position f that the wheel of a car coming along track A in a direction opposite to that in which the cars move when 95 operating the actuating-wheel will engage the point and move it over toward rail B, turn the crank-disk, again bringing the wrist-pin to the position c.

When the lug E' is in position a, the turning of the wheel by the engagement of the foot R with said lug moves the wrist-pin in the direction indicated by the arrow and tends to move the switch-point toward rail B until the dead-center of the crank is reached; 100 but as said point is against rail B when the wrist-pin is at c it cannot move farther in that direction, and therefore the spring N' will be compressed during the movement of the wrist-pin from c to g. During the movement of the wrist-pin from g to h the switch-point is moved from rail B into contact with rail A, the spring N and N' being stiff enough to hold the head L³ in the center of the cylinder against the resistance of the switch-point, and during the movement of the pin from h to d the spring will be compressed, giving the switch-point a heavy thrust to insure its contacting the rail A firmly. As soon as the foot disengages the lug E' at position 105 b the spring N, being under tension, will turn the wrist-pin backward to h and the lug E will be turned backward to position i. The wrist-pin is turned each time not quite to the dead-center—that is, position d is above the 110

dead-center—so that the spring will act to turn the crank-disk and actuating-wheel backward, and the wrist-pin will never be moved past the dead-center by the inertia of the parts. It will thus be seen that no matter by what means the switch-point is operated the actuating-wheel will always be in a position to be operated by the foot on the car and will always be in such a position relative to the switch-point that said point will be thrown in the proper direction. In this construction there is no possibility of the parts getting out of time by the crank-disk being thrown past the dead-center, and should any obstruction get in between the switch-point and rail the spring will simply be compressed when the actuating-wheel is contacted by the foot, and no injury will result to the parts.

In this construction springs are not relied upon to actuate any of the parts, every movement being positive, and therefore is not liable to get out of order or fail in its operation.

Having thus fully described my invention, what I claim is—

1. The combination of a switch-point having a limited throw, a crank having a greater throw than the throw of the switch-point, means adapted to be actuated from a moving car for turning said crank in one direction, and means connecting the crank and switch-point for transmitting motion from said crank to the switch-point and adapted to yield to allow the crank to be revolved when the switch-point has reached the end of its throw.

2. The combination of a switch-point having a limited throw, a crank having a greater throw than that of the switch-point, means adapted to be actuated from the moving car for turning said crank, a divided connecting-rod pivotally secured at its outer ends to the crank and switch-point, and means interposed between the adjacent ends of the connecting-rod to form a yielding connection between said ends.

3. The combination of a switch-point having a limited throw, a crank having a greater throw than the throw of the switch-point, means adapted to be actuated from a moving car for turning said crank, a divided connecting-rod pivotally secured at one end to said crank and at its opposite end to the switch-point, a cylinder secured to one of the two adjacent ends of said connecting-rod, a head on the opposing end of said rod and within said cylinder, and springs within said cylinder engaging said head and the ends of the cylinder.

4. The combination of a switch-point having a limited throw, a crank having a greater throw than the throw of the switch-point, a longitudinally-yielding connecting-rod pivotally secured at one end to said crank and at its opposite end to the switch-point, a vertically-disposed actuating-wheel having a series of lugs adapted to be engaged by means

carried by a car, and means for transmitting motion from said actuating-wheel to said crank.

5. In a switch-operating mechanism, the combination of a switch-point having a limited throw, a crank having a greater throw than the throw of the switch-point, a longitudinally-yielding connecting-rod connecting said crank and switch-point, a casing located within the road-bed and provided with a top having a longitudinal groove, a vertically-disposed actuating-wheel having a series of lugs projecting upward through the top of the casing and into the groove, a bevel-gear actuated by said wheel, a longitudinal shaft to one end of which the said crank is secured, and a bevel-gear on the opposite end of said shaft in mesh with the aforesaid bevel-gear.

6. In a switch-operating mechanism, the combination with a switch-point, an actuating-wheel journaled in a casing in the road-bed, and means for transmitting motion from said actuating-wheel to the switch-point; of a vertically-movable bar carried by a car, a foot, a hinge connecting said foot to said bar, a spring to normally hold said foot extended in line with the bar, and means for moving said bar longitudinally to lower the foot into engagement with said actuating-wheel.

7. In a switch-operating mechanism, the combination with a switch-point, an actuating-wheel, journaled in a casing in the road-bed, and means for transmitting motion from said actuating-wheel to the switch-point; of a bracket carried by the car and provided with a bearing, a vertically-movable bar in said bearing, a head on said bar, a spring sleeved on the bar between the head and bracket, a foot hinged to the lower end of said bar at the rear side of said bar and foot, forward extensions on said bar and foot, a spring secured at its ends to said extensions, a toggle-lever secured at its ends to the bracket and said bar, and a rod pivoted to said toggle-lever to actuate the same.

8. In a railway-switch-operating mechanism, the combination with a switch-point having a limited throw; of a casing located within the road-bed adjacent to the switch-point, a shaft extending longitudinally of the road-bed and journaled in a bearing on the casing at one end, a crank-disk secured to the end of said shaft within the casing, a divided connecting-rod pivotally secured at one end by a wrist-pin to said crank-disk, a stud projecting downward from the switch-point to which the connecting-rod is pivotally secured at its opposite end, a cylinder secured to one end of the adjacent ends of the divided connecting-rod, a head on the opposing end of said rod which extends within said cylinder, coiled springs within said cylinder, each engaging at one end, an end of the cylinder and at their opposite ends, opposite sides of the head, a

casing located in the road-bed at some distance from the first-named casing and provided with a top having a longitudinal groove, a transverse shaft mounted in bearings in the last-named casing, an actuating-wheel secured to the transverse shaft and having a series of lugs to project into the groove in the top of the casing, a bevel-gear secured to said transverse shaft, a bevel-gear secured to the end of the longitudinal shaft and in mesh with

the gear on the transverse shaft, and means carried by the car for operating the actuating-wheel.

In testimony whereof I affix my signature in presence of two witnesses.

OLIVER D. HUNT.
